UNITED STATES PATENT OFFICE.

ROBERT A. LIPSCOMB, OF HOLT, ALABAMA.

FUEL AND PROCESS FOR BURNING SAME.

Application filed June 27, 1921. Serial No. 480,884.

To all whom it may concern:

Be it known that I, ROBERT A. LIPSCOMB, a citizen of the United States of America, residing at Holt, in the county of Tuscaloosa and State of Alabama, have invented 5 certain new and useful Improvements in Fuel and Processes for Burning Same, of which the following is a specification.

This invention relates to a novel type of 10 fuel and an improved process for the most efficient burning of the same.

My invention contemplates the production of an improved type of fuel especially adapted to maintain an elongated and substantially uniformly heated zone of heat interception, which for boilers will be relatively short compared to nodulizing and cement kilns which require, for ideal operation, a 15 very long zone of heat interception which 20 will be free from zones of heat sufficiently intense to cause fusion.

My invention contemplates the production of a fuel capable of producing the above results by the combination of fuel particles, 25 part of which are of such quick burning character as to be readily consumed to produce the requisite initial zone of heat interception in passing through which the other slower burning particles will become ignited 30 and as they burn will extend the zone of heat interception to the desired length. The two different grades of particles may be obtained either by the selection of fuels having different percentages of volatile matter or by the 35 combinations of different sized particles of the same or similar fuel. Obviously, where the fuel is composed of particles carefully selected as to size, as for instance, a definite percentage of finely ground fuel mixed with 40 a definite percentage of much coarser particles of the same fuel, the latter will take longer to be consumed, and as my invention contemplates introducing the fuel aggregate by means of an air blast so that the particles 45 are carried on an air or gas current while being consumed, it follows that the slower burning particles will extend the length of the zone of heat interception and increase the uniformity of its temperature, it being 50 noted that the reduction in the percentage of the total fuel consumed near its entrance

in the combustion chamber will tend to reduce the objectionably high temperatures which tend to exist there.

My invention further contemplates the 55 selection of a high carbon fuel such as is available in ideal form in coke breeze at present generally considered a waste product, and the combining with this of a relatively lower carbon fuel having a high percentage of volatile matter such as waste culm 60 from bituminous coal washings, crushed bituminous coal, or, under certain conditions, gas.

My invention contemplates the reducing 65 of these fuel elements to a finely pulverized condition and their mixture in such relative proportions as to give to the resultant fuel aggregate a sufficient percentage of quickly 70 burning highly volatile fuel to sustain the 75 character of combustion in the initial combustion zone necessary to produce the requisite temperatures for the ignition and the ultimate complete consumption of the slow burning high carbon or coke element of the 80 fuel. In utilizing a fuel of this character so as to produce the maximum heating efficiency therefrom, my invention contemplates the discharge of the pulverized aggregate by air blast into a combustion chamber which 85 may take the form of a boiler furnace, a cement kiln, or a kiln for nodulizing metallic products. In all of these uses the highest heating efficiency will be obtained if the temperature produced by the combustion of the 90 fuel can be sustained within approximate control and with substantial uniformity throughout a long zone of combustion, as by this means the objections to a restricted extremely heated zone, are avoided as well 95 as the many physical disadvantages resulting from localized intense heat which it has not heretofore been possible to overcome.

My invention is based on the theory that the ideal fuel will be obtained when one is 95 found that is capable of sustaining a moderately intense heat throughout an extremely elongated zone, and this is obtained by my proposed fuel in the manner which will now be described.

Assuming, for the sake of illustration, 100 that my improved fuel as last above de-

scribed is to be burned in a nodulizing kiln where ideal combustion conditions would call for a uniform and sustained temperature throughout the major portion of the 5 kiln. Under such conditions having pulverized and mixed the high and low carbon fuels in the manner above described, the fuel aggregate is discharged with an air blast into one end of the kiln. The finely pulverized particles of bituminous coal or culm 10 being high in volatile matter will become immediately ignited and will burn quickly at a relatively lower temperature than the high carbon fuel would burn if ignited at this 15 point. The combustion of this part of the fuel aggregate takes place in a short initial combustion zone in which the highly volatile fuel elements will produce a sufficient temperature, as the high carbon fuel particles 20 are carried along through it, to cause their ignition and subsequent gradual combustion as they traverse the combustion chamber. The desired results flow from this method of combustion of the fuel because 25 the initial combustion of the low carbon high volatile fuel will be quick and of relatively low temperature while the combustion of the high carbon non-volatile fuel will be slower and at a relatively higher 30 temperature which will be sustained throughout a long zone of travel of the high carbon fuel particles which will be ultimately consumed at the end of a travel, the length of which is determined by the draft 35 conditions in the kiln, the size of the particles, the desired operating temperatures in the kiln, and the regulation of the admission of oxygen. These four factors determine the length of the zone of active combustion 40 of high carbon fuel obtained and the temperature therein as follows. If the relative proportions of the low carbon fuel component to the high carbon fuel component be increased the aggregate length of the zone of 45 active combustion will be decreased in proportion to the decrease in the percentage of carbon in the aggregate; by decreasing the relative percentage of the low carbon fuel component within the limits which will enable 50 it to ignite the high carbon fuel, the length of the zone of active combustion will be increased; by increasing or diminishing the volume of air admitted I can accelerate or retard the rate of combustion of the high 55 carbon fuel component and thus control the length of the combustion zone; and by regulating the draft, the rate of travel of the burning fuel particles can be controlled and the length of the combustion zone regulated. 60 A fuel aggregate composed of the pulverized and larger sized particles in suitable proportions can be used to produce the initial and extended zones of combustion just as above described and by varying the relative proportions of large to small particles 65

the length of the heat interception zone can be regulated.

It will be obvious that the mobility of my improved fuel during its combustion is an important and essential factor in my combustion process because by this means I am enabled to take advantage of the movement of the burning fuel particles so as to extend the zone of active combustion and it is in this respect that my invention distinguishes 70 most clearly from the combustion of previous fuel mixtures in which coke and various grades of coal have been combined but in which they were burned in fixed location.

My invention also distinguishes in important respects from the practice heretofore obtaining of burning pulverized coal, whether anthracite or bituminous, or a mixture of the two, under boilers, because in all such fuels all particles have possessed the 80 volatile matter to a high degree as compared with coke and it has not been discovered that by their sizing or use selectively the 85 lengthening of the zone of active combustion and the maintenance of a substantially uniform temperature throughout said zone, was possible. It is important, in obtaining the 90 results which I contemplate, that the high carbon fuel shall have no appreciable volatile matter and especially that hydrogen and combined moisture should not be present in appreciable quantities as these either 95 counteract or disturb the effects desired. It is the absence in appreciable degree of volatile matter, combined moisture and hydrogen in the coke which enables the most practical 100 control and regulation to be obtained, as the action of the carbon particles under the known conditions in the combustion zone can be very accurately determined, but this is 105 not possible where the high carbon fuel carries appreciable percentages of volatile matter, hydrogen and combined moisture.

My invention is of especial importance as a fuel for use in, and as a method of firing, kilns, and particularly nodulizing kilns, where ideal conditions obtain when the combustion zone can be extended as far as possible through the kiln and excessive temperatures of fusion zones avoided at the discharge end, as such excessive temperatures in a concentrated zone tends both to glaze the nodules and to reduce the quantity and quality of the product.

My invention therefore in its preferred 120 form consists in mixing coke or coke breeze with coal or culm from coal washers pulverized to a degree of fineness that will be required by the rate of combustion desired, and in such proportions as will develop the 125 most economical calorific intensity for the use contemplated.

The calorific intensity of my improved fuel depends not only on the quantity of heat evolved, but also on the rate of combustion 130

and the capacity of the products of combustion to absorb the heat. For example, the oxidation of wood during slow decay releases the same number of heat units as if the wood were cast into a fire and burned, but the calorific intensity attained in the two cases is very different. The calorific intensity may be calculated if the above factors are known, or it may be measured directly by 10 thermometers, pyrometers, or any device which is affected by changes of temperatures.

The calorific intensity of a given fuel is the ratio between its power to develop heat and the power of the resulting products 15 of combustion to absorb the heat produced. For example, the calorific intensity of carbon when burned in an atmosphere of oxygen alone is found to be 6,388 degrees F. When, however, the combustion of carbon 20 takes place in oxygen of the air with its accompanying nitrogen, the products of combustion are increased by just that quantity of nitrogen, which, in turn, absorbs its share of heat developed and the resulting temperature 25 is correspondingly low or 3,127 degrees F. The soft coals contain from 50 to 75 percent of carbon and from 20 to 40 percent of combustible gases. These gases also contain a large percentage of carbon 30 combined with hydrogen, and are generally known as hydro-carbon gases. Carbon has a strong affinity for oxygen at elevated temperatures, and when burned in the presence of air or free oxygen it is capable of forming 35 two oxides, CO, known as carbon monoxide, and CO₂ known as carbon dioxide, or carbon anhydride. Both CO and CO₂ are fixed gases, transparent and invisible, but they differ radically in character. CO is an 40 unsaturated compound capable of taking up another atom of oxygen and forming CO₂. In other words, it is combustible. It burns 45 with a blue flame which is familiar to us in hard coal or coke fires, giving very little light but much heat. CO₂ on the other hand, is a completely saturated compound and can 50 take up no further additions of oxygen. It is therefore incombustible. It is a heavy gas, being about one and one-half times as heavy 55 as air. The coke or coke breeze used has a maximum of CO₂ and a minimum of CO, hence its substitution for coal.

The theoretical temperature of the combustion of carbon to the condition of CO in 55 the presence of air is 2270 degrees F. The theoretical temperature of CO burned in air is somewhat higher than that accompanying its formation or 3080 degrees F. It is therefore evident that the calorific intensity of 60 any given fuel is based, to a large degree, on the flexibility of the control of the volatile and combustible matter as compared with carbon.

By properly mixing the above-named materials, the length of the zone of combustion

and the temperatures therein can be controlled, and, in rotary kilns for nodulizing iron bearing materials, the ability to control the zone of incipient fusion shows the following advantages, to-wit:—

70

Increased production.

Control of ring in kiln.

Less fuel per ton of product.

Easy control of temperatures.

Increased porosity.

75

Reduction of fines.

Increased production is due to uniform temperatures through a much longer area of the kiln than is possible when coal only is used. The zone of incipient fusion where 80 coal is used is not more than 20 to 25 feet, whereas, when an equal mixture of coal and coke breeze that will pass a 35 mesh screen is used, it is from 50 to 60 feet. The long zone of critical temperature necessarily subjects 85 the material to longer treatment at this temperature, which in turn accounts for the absence of the translucent and glass-like structure of the iron silicate enveloping the oxide of iron, usually noticed when contracted 90 zones of very high temperature are used. The same application of critical temperature will obtain in cement kilns with equally advantageous results.

The absence of ring formation in kilns is 95 due to the excess amount of carbon and lower volatile and combustible matter in my improved fuel as compared with coal. The high carbon and low volatile matter naturally requires more air and longer time to 100 complete combustion than does the coal which explains the longer zone of incipient heat interception, and the absence, to a marked degree, of the contracted zone of 105 heat interception of a temperature sufficiently high to cause fusion.

Lower fuel cost and easy control of temperature is due primarily to the use of coke or coke breeze, as coke breeze is considered 110 waste product, and the cost may be further reduced by the use of culm, or washer waste from coal washers, as a low carbon mix with the coke breeze.

My invention contemplates the use of a mixture of high carbon material with low 115 carbon, high volatile and combustible matter, the same being pulverized to a condition of very minute particles. This finely divided material to be burned in a current of mixture of air. Any of the devices designed to handle pulverized coal will handle 120 this pulverized fuel which is available for use in any and all metallurgical devices for heat treatment, cement kilns, steam boilers, brick kilns, potteries, glass furnaces or any 125 heating or fuel fed device wherein any carbonaceous material can be used to generate heat.

In the illustrative drawings of a typical apparatus for firing a nodulizing kiln.

130

Fig. 1 is a view in elevation of the fuel bin and fuel delivery mechanism with the kiln shown in section and broken away.

Fig. 2 is a diagrammatic view indicating the fusion zones of the fuel compartments.

As illustrated, 1 is a hopper filled with a typical fuel aggregate 2 pulverized to pass through a 35 mesh screen and composed of one-half coke breeze and one-half coal, preferably in the form of a waste product, such as carbon or washer waste. This finely pulverized and thoroughly mixed aggregate is fed by a screw 3 into a feed chute 4 which delivers it into an air blast pipe 5 by which it is blown with a blast of air through the nozzle 6 into the kiln 7. The nozzle enters the kiln through the end door 8 which affords control of the volume of air admitted. The low carbon volatile constituent of the fuel is burned in the incipient combustion zone indicated typically in Fig. 2, whereas the high carbon fuel, ignited in the incipient combustion zone is consumed throughout the greatly extended zone indicated.

When I refer to an "air current" I intend to include any oxygen bearing current of gas by which the burning particles of fuel are carried and which supplies to them the needed oxygen for their sustained combustion.

Having thus described my invention, what I claim as new and desire to secure by Letters Patent, is:—

1. The hereindescribed process for producing an elongated and substantially uniformly heated zone of heat interception, which consists in blowing into a combustion chamber finely divided particles of coke in combination with sufficient volatile combustible matter to produce by its combustion an initial temperature which will ignite the particles of coke.

2. The hereindescribed process for producing an elongated and substantially uniformly heated zone of heat interception, which consists in blowing into a combustion chamber finely divided particles of highly carbonaceous material substantially free of volatile matter, hydrogen and combined moisture in combination with sufficient volatile combustible matter to produce by its combustion an initial temperature which will ignite the particles of said carbonaceous material, and regulating the zone of combustion of the carbonaceous material by control of the volume of oxygen admitted.

3. The hereindescribed process for producing an elongated and substantially uniformly heated zone of heat interception, which consists in blowing into a combustion chamber finely divided particles of coke in combination with sufficient volatile combustible matter to produce by its combustion an initial temperature which will ignite

the particles of coke, and regulating the zone of combustion of the coke by control of the volume of oxygen admitted.

4. The hereindescribed process for producing an elongated and substantially uniformly heated zone of heat interception, which consists in blowing into a combustion chamber finely divided particles of coke breeze in combination with sufficient volatile combustible matter to produce an initial zone of combustion in passing through which the particles of coke will be ignited, and regulating the length of the zone of combustion of the coke particles by control of the volume of oxygen admitted and by the relative percentage of coke to combustible matter in the fuel aggregate.

5. The hereindescribed process for producing an elongated and substantially uniformly heated zone of heat interception, which consists in blowing into a combustion chamber finely divided particles of coke in combination with sufficient highly volatile combustible matter and oxygen to produce by its combustion an initial temperature which will ignite the particles of coke as they pass therethrough and regulating the zone of combustion of the coke by control of the volume of oxygen admitted, by the relative percentage of coke to combustible matter in the fuel aggregate, and by the regulation of the velocity of flow of the fuel particles responsive to the draft condition in the combustion chamber.

6. The hereindescribed process of producing an elongated and substantially uniformly heated zone of heat interception, which consists in discharging a mixture of pulverized coke and coal by means of an air blast into a combustion chamber, regulating the admission of oxygen to the chamber, and restricting the volume of coal to that requisite to ignite the particles of coke in the initial combustion zone, leaving the latter to complete their combustion as they traverse the combustion chamber.

7. The hereindescribed method of firing kilns, which consists in providing a pulverized fuel aggregate composed of coke and coal, restricting the relative percentage of coal to that necessary to produce a predetermined temperature in the initial combustion zone, and controlling the rate of combustion of the particles of coke ignited in the initial combustion zone by a regulation of the volume of oxygen admitted to the kiln.

8. The hereindescribed method of firing kilns, which consists in providing a pulverized fuel aggregate composed of coke and coal, restricting the relative percentage of coal to that necessary to produce a predetermined temperature in the initial combustion zone, and controlling the rate of combustion of the particles of coke ignited in the initial combustion zone by a regulation

of the volume of oxygen admitted to the kiln and of the draft through the kiln.

9. The hereindescribed method of firing a nodulizing kiln to produce therein an extended zone of substantially uniform temperature below that required for fusion, which consists in blowing into the discharge end of said kiln a pulverized fuel aggregate composed of high carbon non-volatile fuel 5 matter in combination with relatively high volatile low carbon fuel matter so proportioned as to produce, by the combustion of the latter alone a relatively short zone of

10 incipient fusion having a predetermined temperature, and to extend said zone of incipient fusion by the combustion of the particles of high carbon material ignited in said initial zone, and controlling the length of heat of said extended zone by a regulation of the volume of oxygen admitted and the rate of travel of the burning high carbon particles.

In testimony whereof I affix my signature.

ROBERT A. LIPSCOMB.
